[57] **CLAIM**

The ornamental design for a shopping cart, as shown and described.

DESCRIPTION

FIG. 1 is a perspective view of a shopping cart showing my new design;

FIG. 2 is a side elevational view thereof;

FIG. 3 is a side elevational view of the side opposite that shown in FIG. 2;

FIG. 4 is a front elevational view thereof;

FIG. 5 is a rear elevational view thereof;

FIG. 6 is a top plan view thereof;

FIG. 7 is a bottom view thereof; and,

FIG. 8 is a perspective view of a second embodiment of the shopping cart, the sole difference between the first embodiment being in the different material of storage container.
